COLLAPSIBLE CARDBOARD COUNTER
BASKET

John V. Horr, North Tarrytown, N. Y., assignor
to Einson-Freeman Co., Inc., Long Island City,
N. Y., a corporation of Delaware

Application February 7, 1947, Serial No. 727,147

10 Claims. (Cl. 229—41)

1 My present invention relates generally to collapsible cardboard devices, and has particular reference to a counter basket or the like.

The present improved structure is designed primarily to be used on store counters or the like, to accommodate merchandise such as packages or cans, but it will be understood that the broader phases of my invention are applicable to baskets or containers intended for other purposes.

A general object of the invention is to provide certain improvements in the known type of collapsible counter basket which consists essentially of a peripheral wall formed of hingedly connected areas, and a collapsible floor formed of articulated panels. A basket of this general character is described and illustrated in my earlier patent, No. 2,114,492.

A more particular object of the present invention resides in the association, with a collapsible basket of this general character, of elements defining a secondary collapsible structure. In the preferred form of the invention, the secondary structure comprises a basket of smaller dimensions than the main basket, articulated to the floor panels of the main basket.

My invention aims to provide a simple inexpensive cardboard structure, readily adjustable from a substantially flat collapsed condition into a set-up condition in which there is defined a main outer basket and a subordinate inner basket of smaller dimensions. Such a structure has many uses in the field of merchandise display, as will readily be understood by those skilled in the art.

Among the particular features of the new construction is an arrangement of parts whereby the floor of the main basket consists of articulated panels having portions which approach a common vertical plane when the basket is collapsed and approach a horizontal alignment when the basket is set up, and whereby the secondary structure includes opposed sections which are hinged to said panel portions respectively. This association of parts brings about an automatic set-up and collapse of the subordinate structure as the main basket is adjusted into correspondingly set-up and collapsed conditions.

I achieve the foregoing general objects and advantages, and such other objects and advantages as may hereinafter appear or be pointed out, in the manner illustratively exemplified in the accompanying drawings, in which:

Figure 1 is an elevational cross-sectional view of an improved counter basket of the present character, shown in set-up condition, the sec-

tion being taken substantially along the line 1—1 of Figure 2;

Figure 2 is a plan view of the structure, only the rear display panel being shown in section;

Figure 3 is a cross-sectional view taken substantially along the line 3—3 of Figure 1;

Figure 4 is a view similar to Figure 3, on an enlarged scale, showing the manner in which the structure may be collapsed; and

Figures 5, 6, 7 and 8 are plan views of the blanks of which the structure is composed.

Referring first to Figures 5 and 6, the blanks therein illustrated are composed of flat sheet material such as cardboard. The blank of Figure 15 has five areas 10—14 hinged end-to-end along fold lines 15. These fold lines converge toward a common center so that the five areas may be caused to define the major portion of a peripheral wall. Hingedly connected to the area 12

20 along the line 16 is a panel 17 having the shape of a regular hexagon with one region cut away. More particularly, the panel 17 is defined by an edge 18 extending radially from the center of the hexagon to one corner thereof, by peripheral

25 edges 19, 16, 20, 21 and 22, and by an inwardly directed edge 23 which is perpendicular to the edge 18. The edge 23 is slightly offset from the center of the hexagon so that a notch 24 is formed. The dot-and-dash lines 25 represent

30 fold lines whose functioning will presently become apparent.

The blank of Figure 5 is provided with a similar substantially hexagonal panel 26 defined by peripheral edges 27, 28, 29, 30 and 31, and by reentrant edges 32 and 33 arranged at right angles. A notch 34 is formed at the center. The dot-and-dash lines 35 represent fold lines.

Hingedly connected along the line 28 is an area 36 corresponding in shape and size to the areas 10—14 of Figure 6, and constituting one of the areas entering into the formation of the peripheral basket wall. Attachment areas or flaps 37 and 38 are hinged to the area 36 along the lines 39.

45 Extending outwardly from the areas 37 and 38 are the triangular display panels 40 and 41, respectively, and between these panels there is a larger main display panel 42 bounded in part by the hinge lines 43.

I shall first describe how the blanks of Figures 5 and 6 are assembled to define a main collapsible counter basket. The panels 17 and 26 jointly define a collapsible floor. The notches 24 and 34 are interengaged so as to bring the panels 50 17 and 26 into superposed relationship with the

peripheral edges in registry. The area 14 is then adhesively or otherwise secured to the area 38, and a similar permanent engagement is established between the areas 10 and 37. This defines a structure which is substantially like that shown in my aforementioned earlier patent, although the various panels and areas of the earlier construction are not quite the same as those herein illustrated and described. In set-up condition, the parts of the structure are substantially in the relationships shown in Figures 1, 2 and 3. The floor panels 17 and 26 approach a horizontal alignment, one above the other, defining a double-ply floor for the basket. Extending upwardly from the periphery of this floor is the peripheral wall of the basket defined by the areas 10-14 and 36. Extending upwardly at the rear of the basket is a display area (40, 41, 42) adapted to receive advertising matter of other embellishment. The collapse of the structure is effected by buckling the floor upwardly, as shown in Figure 4. This brings the free end portions of the floor panels into an upward disposition in which they tend to approach a common vertical plane as the device is collapsed to its fullest extent. The areas 11, 12 and 13 of the peripheral wall of the basket tend to align themselves in a single plane, and overlie the areas 10, 36 and 14 respectively.

In the set-up condition of the basket, the fold lines 25 and 35 of the floor panels facilitate a wedging of the two-ply floor into frictional engagement with the peripheral wall of the basket.

In Figures 7 and 8 I have illustrated the two blanks of which the present secondary or subordinate structure is composed. The blank of Figure 7 consists of seven sections 44-50 hingedly connected in side-by-side relationship along lines 51. The lines 51 converge toward a common center so that the sections can be adjusted to form an enclosure defining the peripheral wall of a basket of smaller dimensions. More particularly, the sections 44 and 50 are brought into overlapping relationship and are adhesively or otherwise secured to each other. At the lower or shorter edges of the opposed sections 46 and 49, attachment flaps 52 are provided, being hinged along the lines 53.

The blank of Figure 8 consists of a substantially hexagonal piece 54 formed with a diametric fold line 55 and parallel hinge lines 56. Beyond each of the lines 56 is an attachment flap 57.

The flaps 57 are adhesively or otherwise secured to the sections 46 and 49, respectively, and the attachment flaps 52 are adhesively or otherwise secured to the panels 17 and 26, respectively. This arrangement of parts is shown most clearly in Figures 3 and 4.

It will be noted that the sections 46 and 49 tend to approach each other when the structure is collapsed (Figure 4), and tend to separate when the structure is set up (Figure 3). The section pairs 47-48, 44-45 and the two parts of the floor piece 54 constitute toggles which are interposed between the sections 46 and 49. These toggles tend to collapse when the sections 46 and 49 approach each other.

The desirable result which is achieved by this arrangement of parts will be apparent from the description given. An adjustment of the main basket into a set-up condition, will simultaneously and automatically result in bringing the subordinate basket into a correspondingly set-up condition, shown most clearly in Figures 1, 2 and 75 respectively.

3. A collapse of the main basket, as hereinbefore described (Figure 4), will bring about a simultaneous and automatic collapse of the subordinate basket.

Upon completion of manufacture of the device, it is adjusted into collapsed condition, and stored or shipped in this condition, either singly or in association with other similar collapsed structures. The ultimate user is not called upon to perform any difficult manipulations. By merely grasping the main display panel, the structure tends to fall into the set-up condition, and a slight downward pressure upon the floor panels 17 and 26 is all that is required by the user to establish the completely set-up condition in which two counter baskets, one inside the other, are immediately available for use.

It will be understood that the shapes and proportions of the parts, and other details, may obviously be modified by those skilled in the art without necessarily departing from the spirit and scope of the invention as expressed in the appended claims.

Having thus described my invention and illustrated its use, what I claim as new and desire to secure by Letters Patent is:

1. In a collapsible cardboard counter basket, a peripheral wall comprising hingedly connected areas including a pair of opposed areas, a bottom wall comprising a pair of interlocked panels hinged to said opposed areas respectively, and a secondary collapsible structure articulated to said panels and controlled thereby.

2. In a collapsible cardboard counter basket, a peripheral wall comprising hingedly connected areas including a pair of opposed areas, a bottom wall comprising a pair of interlocked panels hinged to said opposed areas respectively, and a secondary collapsible structure articulated to said panels and controlled thereby, said secondary structure comprising a basket of smaller dimensions than the main basket.

3. In a collapsible cardboard counter basket, a peripheral wall comprising hingedly connected areas including a pair of opposed areas, a bottom wall comprising a pair of interlocked panels hinged to said opposed areas respectively, and a secondary collapsible structure articulated to said panels and controlled thereby, said secondary structure comprising hingedly connected sections defining the peripheral wall of a basket of smaller dimensions than the main basket.

4. In a collapsible cardboard counter basket, a peripheral wall comprising hingedly connected areas including a pair of opposed areas, a bottom wall comprising a pair of interlocked panels hinged to said opposed areas respectively, and a secondary collapsible structure articulated to said panels and controlled thereby, said secondary structure comprising hingedly connected sections defining the peripheral wall of a subordinate basket, and a collapsible floor for said subordinate basket.

5. In a collapsible cardboard counter basket, a peripheral wall comprising hingedly connected areas including a pair of opposed areas, a bottom wall comprising a pair of interlocked panels hinged to said opposed areas respectively, and a secondary collapsible structure articulated to said panels and controlled thereby, said secondary structure comprising hingedly connected sections defining the peripheral wall of a subordinate basket, two of said sections being hingedly connected at their lower edges to said panels respectively.

6. In a collapsible cardboard counter basket, a peripheral wall comprising hingedly connected areas including a pair of opposed areas, a bottom wall comprising a pair of interlocked panels hinged to said opposed areas respectively, and a secondary collapsible structure articulated to said panels and controlled thereby, said panels having portions which approach a common vertical plane when the basket is collapsed and approach a horizontal alignment when the basket is set up, said secondary structure including opposed sections hinged to said panel portions respectively, said sections approaching each other as said panel portions approach each other and moving apart as said panel portions approach said horizontal alignment.

7. In a collapsible cardboard counter basket, a peripheral wall comprising hingedly connected areas including a pair of opposed areas, a bottom wall comprising a pair of interlocked panels hinged to said opposed areas respectively, and a secondary collapsible structure articulated to said panels and controlled thereby, said secondary structure including a pair of opposed sections hinged to said panels respectively, and toggle elements between said sections.

8. In a collapsible cardboard counter basket, a peripheral wall comprising hingedly connected areas including a pair of opposed areas, a bottom wall comprising a pair of interlocked panels hinged to said opposed areas respectively, and a

secondary collapsible structure articulated to said panels and controlled thereby, said secondary structure including a pair of opposed sections hinged to said panels respectively, and toggle elements between said sections, certain of said toggle elements defining part of the peripheral wall of a subordinate basket, another of said toggle elements defining the floor of said basket.

9. In a collapsible cardboard counter basket, a set of outer hingedly connected areas defining the peripheral wall of a main basket, a set of inner hingedly connected sections defining the peripheral wall of a subordinate smaller basket, a floor for said main basket, and means articulating said subordinate basket to said floor.

10. In a collapsible cardboard counter basket, a set of outer hingedly connected areas defining the peripheral wall of a main basket, a set of inner hingedly connected sections defining the peripheral wall of a subordinate smaller basket, a collapsible floor for said main basket comprising articulated panels adapted to approach a common vertical plane when the basket is collapsed, a collapsible floor for said subordinate basket comprising a toggle element, and means articulating said subordinate basket to said panels so that the set-up and collapse of said subordinate basket is automatically effected by set-up and collapse of said main basket.

JOHN V. HORN.
